(57) **CLAIM**

We claim the ornamental design for a beverage cap liner, as shown and described.

DESCRIPTION

FIG. 1 is a perspective view of a beverage cap liner;
 FIG. 2 is a side view thereof;
 FIG. 3 is a cross-sectional view taken along the 3-3 line of FIG. 1;
 FIG. 4 is a top view thereof; and,
 FIG. 5 is a bottom view thereof.
